UNITED STATES PATENT OFFICE

143,171

DESIGN FOR A VANITY CASE

Walter Dorwin Teague, New York, N. Y., assignor to Illinois Watch Case Co., Elgin, Ill., a corporation of Illinois

Application September 12, 1945, Serial No. 122,042

Term of patent 7 years

(Cl. D86—10)

To all whom it may concern:

Be it known that I, Walter Dorwin Teague, a citizen of the United States, residing at New York, in the county of New York and State of New York, have invented a new, original, and ornamental Design for Vanity Cases, of which the following is a specification, reference being had to the accompanying drawing, forming part thereof, wherein:

Figure 1 is a top plan view of a vanity case, showing my new design;

Fig. 2 is an elevational view of one side face thereof; and

Fig. 3 is an elevational view of the front face thereof.

I claim:

The ornamental design for a vanity case, as shown.

WALTER DORWIN TEAGUE.
